and at this end need to be well located from the bottle neck to permit a smooth and easy entry of the bottle into the discharge chamber. It is also important that the bottle be held in a definite position when admitted into the discharge chamber, and that the bottle be held in a definite position when admitted into the discharge chamber.

UNITED STATES PATENT OFFICE

BOTTLE VENDING MECHANISM

Ralph Warner and Harold B. Smalley,
Bloomington, Ill.

Application March 11, 1948, Serial No. 14,313

7 Claims. (Cl. 312—88)

1

This invention relates to bottle vending mechanism.

The invention is more particularly concerned with a novel release structure for use in bottle vending mechanism.

The present invention is an improvement over the structure disclosed in Patent No. 2,174,712, issued to R. W. Warner, and the primary object of the invention is to provide a release mechanism which is substantially simpler in construction than that of the patent while being equally as effective, whereby it is capable of construction at substantially less cost.

A further object of the invention is the provision of a release mechanism for use in a bottle vending machine which is capable of adjustment for the handling of bottles having different size necks.

Further objects and advantages of the invention will become apparent in the course of the following detailed description, taken in connection with the accompanying drawing, wherein—

Figure 1 is an elevational view of the improved release mechanism as viewed from the bottle entrance side thereof, the casing being shown in dot-and-dash lines for greater clarity of the essential elements entering into the present invention.

Figure 2 is a fragmental view similar to Fig. 1, but showing the position of elements when a bottle is being released.

Figure 3 is a fragmental top plan view showing the operative relation of the release mechanism to other parts of a common bottle vending machine.

Referring now in detail to the drawing, D designates a portion of a dispensing unit or vending machine, such as shown in the above referred to Warner patent, and which includes spaced slats S defining the bottle guide-ways, and a top wall T, a front wall F and a rear wall R defining the discharge chamber adjacent the free ends of the slats S.

The improved release mechanism forming the subject-matter of the instant invention comprises a base 10 upon which successive bottles B rest when admitted through the opening O in wall F from one or the other of the guide-ways.

Suitably secured to the top of the base are bottle-confining brackets 11 and 12, the latter being spaced from a bottle in normal seated position on the base further than the former.

The release mechanism proper includes a metallic trap 13 and an adjustable guide 14. The adjustable guide 14 includes a rounded surface

2

15 engageable by the bottle B when being withdrawn, and the part 15 merges into and overhangs a vertical portion 15' disposed between bracket 12 and a bottle B when in seated position on base 10.

The guide further includes an elongated horizontal portion 16 having a threaded stud 17 extending through an elongated slot 18 in a guide member 19 depending from a plate 20 supported in an opening in top wall T. The portion 16 terminates in a depending flange 16' which opposes a spaced similar flange 22' depending from a horizontal portion 22 carried by plate 20.

A screw 23 extends through flange 22' and has a rounded end engaging flange 16', whereby surface 15 may be moved closer to the trap for narrower-necked bottles, after which a nut 21 on stud 17 is drawn up to lock guide surface 15 in its set position, and the screw 23 is provided with a lock nut 24 to prevent inadvertent turning thereof.

The trap 13 includes a relatively heavy L-shaped casting 26 merging into a flange 27, and the trap includes an arcuate bottle-engaging edge portion 25. The trap is secured to a shaft 28 which extends through the rear wall R and into a well known form of coin-controlled mechanism, the shaft preferably including a squared portion 29 extending through the casting to preclude relative rotation therebetween.

As will be well understood, the shaft 28 is locked against rotation when the trap 13 is in the position of Fig. 1, and upon deposit of a coin, the shaft is unlocked for counterclockwise rotation thereof as well as the trap 13 secured thereto, and upon the trap being returned to the position in Fig. 1, the shaft will be automatically locked.

Thus, the trap 13 is normally in the position in Fig. 1, wherein the arcuate portion 25 is spaced from guide surface 15 sufficiently to permit the neck portion of a bottle B to pass therebetween, but such space is insufficient to permit passage of the wider body portion of the bottle therethrough. Further, in this normal position, the flange 27 is disposed to one side of the opening O thereby permitting a bottle B to be moved into the position shown in Fig. 2.

With the bottle in the position mentioned, a purchaser deposits a coin, which results in unlocking the shaft 28 and thereby freeing the gate 13 for rotation. The bottle may then be grasped beneath the lip thereof and raised as in Fig. 2, which results in counterclockwise rotation of the gate due to pressure of the bottle on the arcuate portion 25, and as the gate rotates sufficient space

between same and guide surface 15 will be provided to permit passage of the body portion of the bottle.

This increase in distance between the gate and guide is due to the axis of shaft 28 being substantially close to the inner wall of the adjacent leg of the L-shaped casting while being at a substantial distance from the portion 25.

It is to be noted that when the bottle is being withdrawn, as in Fig. 2, the flange 27 closes the admission opening O, thereby preventing another bottle from being moved into releasing position until after the gate has returned to its normal position, as in Fig. 1.

When the bottle is finally withdrawn, the greater portion of the mass of the gate will be disposed to the right of shaft 28, and this unbalanced weight in the gate will tend to return it to its normal position of Fig. 1, the gate, however, being positively moved to such normal position by the spring 28 which acts on shaft 28 and is a well known element of a coin-controlled mechanism.

While we have disclosed the invention in accordance with a single specific embodiment thereof, such is to be considered as illustrative only, and not restrictive, the scope of the invention being defined in the following claims.

What we claim and desire to secure by U. S. Letters Patent is:

1. A release mechanism for use in a bottle-vending machine having spaced front and rear walls with a bottle-admission opening in the front wall; said mechanism comprising a guide overhanging the opening at one side thereof and a gate disposed between the walls at the opposite side of the opening, said guide and gate in the normal position of the parts including opposed portions spaced apart a substantially less distance than the width of said opening and being positioned for receiving the neck of a bottle therebetween, and said gate being rotatably supported for movement from said normal position through an angle of substantially 90° and including surfaces unequally spaced from the axis of rotation whereby sufficient space is provided between the guide and gate to permit the passage of the body of the bottle therebetween as the bottle is vertically withdrawn from between said walls.

2. The structure according to claim 1, wherein said guide is adjustably supported for move-

ment thereof toward or from the gate for the handling of bottles having different size necks.

3. The structure according to claim 1, wherein said gate includes a flange which closes said opening as the gate is rotated to the bottle-releasing position.

4. A release mechanism for use in a bottle-vending machine having front, rear and top walls and a bottle-admission opening in the front wall; said mechanism comprising a guide and a gate disposed between said walls and at opposite sides of said opening in the normal positions thereof and defining therebetween a bottle-receiving space, said guide and gate having opposed portions overhanging said opening and spaced apart a distance to receive therebetween the neck of a bottle and said distance being less than the diameter of the body of the bottle, said gate being supported by a coin-controlled mechanism shaft and the gate being rotatable with the shaft from said normal position through an angle sufficient to swing the said portion of the gate away from the cooperating portion of the guide to permit release of the body of the bottle from therebetween.

5. The structure according to claim 4, wherein said shaft is connected with the gate adjacent said neck-receiving portion thereof whereby the weight of the gate when rotated to bottle-releasing position will be unbalanced relative to the shaft and the gate will accordingly be assisted by gravity in its return to normal position.

6. The structure according to claim 4, wherein said gate is provided with a flange movable over said opening as the gate is rotated to bottle-releasing position.

7. The structure according to claim 4, wherein said guide is adjustably supported from said top wall for movement relative to said gate for the handling of bottles having different size necks.
